MILK DELIVERY BOX

John A. Hopwood, Great Neck, N. Y.

Application March 21, 1936, Serial No. 70,040

15 Claims. (Cl. 217—19)

This invention relates to milk delivery boxes and is directed more particularly to a box adapted for the handling of milk in paper containers of frusto conical form. In boxes ordinarily employed for the handling of milk, the interior of the box is divided into a series of compartments adapted to receive glass milk bottles individually, but such boxes are not suitable for the delivery of milk when packaged in conical paper containers. The walls of the containers are not sufficiently strong to stand lateral impact of the containers against the partitions in a box, and when such impact occurs, it deforms the container and is apt to rupture the same. Consequently, experience has shown that, when paper containers are to be handled, they must be packed in an entirely different way and in a box adapted for this particular purpose, and the object of the invention is to provide such a box.

In practically carrying out the invention, the box is provided with four walls and a suitable bottom which may conveniently be in the form of spaced apart slats on which the containers are adapted to rest. Said containers, in accordance with the present invention, are supported on the bottom of the box in alternate upright and inverted condition, so that said containers interfit with one another to form a tight package, such as will tend to minimize lateral shifting of the containers. Such lateral shifting is further minimized by providing spacer strips on the interior walls of the box, located substantially midway of the height of the containers above the bottom of the box and adapted to bear against those containers which are positioned next to the walls of said box in a manner to hold them in upright condition and to preclude any tendency of the containers to tilt. By positioning the spacer strips midway of the height of the containers, the strips are adapted to properly cooperate with those containers which are inverted, as well as those which are positioned in upright relation.

To further maintain the containers against shifting the bottom of the box is preferably provided with projections which may extend above the floor of the box or which may be produced by forming recesses in the floor of the box, but, in any event, these projections are adapted to project into the re-entrant tops or bottoms of the containers or both, thus effectually positioning the same in predetermined relation to one another.

As a further and positive safeguard against shifting or rattling of the containers, the box is

provided with a clamping plate adapted to overlie the upper ends of the containers, as they are arranged in interfitting relation within the box, and this plate is constructed to apply a downward pressure on to the upper ends of all of the containers by virtue of an associated clamping device of resilient nature which imparts to the clamping plate a yielding downward pressure and serves to clamp all of the containers firmly in position. The clamping plate is of perforated 10 or openwork character and is positioned sufficiently below the upper open top of the box to provide an ice compartment in which cracked ice or solidified carbon dioxide may be received to maintain the contents of the box at proper 15 temperature.

Features of the invention, other than those adverted to, will be apparent from the hereinafter detailed description and claims, when read in conjunction with the accompanying drawings.

The accompanying drawings illustrate different practical embodiments of the invention, but the constructions therein shown are to be understood as illustrative, only, and not as defining the limits of the invention.

Figure 1 is a plan view of a delivery box embodying the present invention. Certain portions of this view are broken away to show containers beneath the ice shelf, while certain containers are omitted to show the interior of the bottom 30 of the box.

Figure 2 is a section on the line 2—2 of Figure 1, with parts of the clamping device in elevation.

Figure 3 is a fragmental plan view of a modified form of bottom slat.

Figure 4 is a section on the line 4—4 of Figure 3, showing one method of securing the bottom slats to the end walls of the box.

As shown in the accompanying drawings, the box has two side walls 1 and 2 and two end walls 3 and 4 assembled at the four corners of the box to provide a rectangular frame which may be, if desired, reinforced in any appropriate way, such as by corner irons 5. The box is shown 45 as having associated therewith stacking irons 6 at its four corners, although these stacking irons may or may not be employed depending upon conditions. The bottom of the box is shown in the form of a plurality of slats 7 which extend 50 longitudinally across the bottom of the box and are anchored to the opposite end walls 3 and 4 in any suitable way.

The bottom slats 7 are reinforced by a cross brace 8 extending transversely across the middle 55

or the box with its opposite ends turned up and riveted at 9 to the side walls 1 and 2. The bottom edges of the box are shown as armored with metal channel sections 10.

5 The particular box body employed is really immaterial, so far as details of construction are concerned, and may be conventional, the essential features being that it has side and end walls with an appropriate bottom. However, the 10 walls 1, 2, 3 and 4 should be somewhat higher than the usual, so as to extend above milk containers positioned in the box for reasons presently stated.

15 Milk containers of frusto conical form, indicated at 11, are adapted to be placed in upright, spaced apart, relation within the box with interposed or interfitted similar containers 12 arranged in inverted relation, and all resting on the bottom slats 7, as shown in Figures 1 and 2. 20 I find it desirable to provide spacer strips 13 along the insides of the box at an elevation midway of the height of the containers 11 and 12, and these spacer strips are of such width that they will space the containers midway of their 25 height from the sides and ends of the box and thus maintain them against tilting irrespective as to whether the containers are upright or inverted. These strips may be positioned along all four walls of the box or merely along two 30 opposite walls. This is optional. They particularly assist in the placement of the containers in the box in proper position.

35 To further assist in the positioning of the containers in the box in proper relation to one another, those portions of the bottom which underlie the inverted containers are preferably provided with projections 14, shown as circular in form and of a size to project into the recess in the small end of the container. In practice these 40 projections 14 are preferably of a height to extend to the base of the recess of the container, so that, when a container is inverted and resting on one of these projections, the sealing cap 15 will seat on the top of the projection and 45 thus be reinforced and thereby precluded from dislodgment by the liquid in the container if the box is dropped or forcibly set down. This arrangement is clearly shown in Figure 2, wherein the projection 14 shown in section is of a 50 height to tightly clamp the sealing cap 15 between said projection and the metal seat 16 with which such containers are usually provided. The upper face of the projection 14 is here shown as 55 flat, but it may be slightly concave or re-entrant, if desired, so that the clamping action referred to is obtained without pressure against the cap 15 at its center. This will allow of slight bulging of the cap, such as frequently occurs, particularly during cold weather.

60 The projections 14 are shown in Figure 2 as formed separately from the bottom slats 7 and received in seats 17 in the latter to be held in place therein by screws, brads or otherwise. If desired, however, the projections may be otherwise formed. They may be made independently of the bottom slats and secured thereto in any appropriate way or they may be formed from the material of the bottom slats.

65 One way of accomplishing this result is shown 70 in Figures 3 and 4 where the upper faces of the bottom slats are grooved or channeled, as shown at 18, to provide projections 14 to fit into the small ends of the containers and also larger projections 14' to fit into the recesses in the upper ends of the containers, this being prefer-

able with this type of construction because the upper ends of all of the containers should occupy substantially the same horizontal plane, in order that a pressure plate may cooperate with all of them in the manner next to be described.

5 The pressure plate 19 is made of a size to fit easily into the interior of the box and rest upon the tops of the containers. It may be formed of any appropriate material and in a wide variety of ways. Essentially it embodies a platform having openings therein and sufficiently strong that, when pressed tightly against the tops of the containers, it will hold them in place. It may be made in the form of an appropriate frame having therein a heavy wire mesh or 15 screen or it may be made of other material, but I find it economical, sanitary and efficient to make the pressure plate 20 of openwork sheet metal having an appropriate peripheral binding 21, which reinforces and strengthens the 20 same. The perforations 22 may be made of a size convenient to support ice without permitting reasonably sized pieces of the ice to fall through.

25 The pressure plate is adapted to be laid on 25 the tops of the containers and then placed under elastic pressure in the direction of the latter. Various means may be employed for this purpose, but I have found it convenient to employ a clamping strip 23 of resilient metal 30 pivoted at the center of the plate by a pivot 24 and of a length greater than the transverse interior dimension of the box. The side walls of the box, at about the level of the upper ends 35 of the containers, are provided with longitudinally extending slots 25, the upper edges of which may be provided with wear plates 26 of channel section and the clamping strip is adapted to be rotated about the pivot 24 and placed under tension, so as to enter the slots 25 and 40 lock the pressure plate 19 in position with the elastic pressure of the clamping strip imposed thereon in the direction of the containers. A single clamping strip is shown in the drawings, although two or more, placed in spaced apart 45 relation longitudinally of the box, may be employed and these clamping devices may be of other construction without departing from this invention.

45 It will be noted that the clamping strip 23 50 has arched portions 27. These are provided in order that the strip may be more easily gripped and manipulated and to further increase the resiliency of said strip, although they may be omitted if desired and the strip made straight 55 or flat. It should be so associated with the plate, however, that it will clamp the plate under pressure sufficient to hold it in position and, in turn, clamp all of the containers between said plate and the bottom of the box.

60 It will be noted that the box is made somewhat deeper than the heights of the containers, the purpose being to provide, above the pressure plate 19, an ice containing chamber 28 adapted to receive cracked ice or solidified carbon dioxide, in such manner that the same will rest upon the pressure plate 19, which is thus adapted to operate as an ice shelf to retain the ice from falling through the box.

65 The perforations in this ice shelf allow free 70 drainage of water and further permit the circulation of cooled air downwardly about the containers in order that they may be retained at the proper temperature without actual contact with the ice.

The present invention provides for the compact and efficient transportation of milk in frusto conical containers. The interfitting of the containers in alternate upright and inverted positions allows a maximum number of containers to be packed in a box of minimum size, while the various adjuncts to which I have referred in connection with the position of the containers permit me to properly handle a box containing less than a sufficient number of containers to fill the same. In other words, even though the box contains less than a sufficient number of containers to fill the same, each and every container therein will be locked in position, so that it cannot shift and this locking or clamping, which I have described, is such as not to place any undesirable stresses or pressure on any part of the container. The pressure transmitted through the pressure plate is taken longitudinally through the side walls of the containers where it can do no damage, so that the containers are, in fact, suspended between their ends, and their sides, which are unable to withstand much radial pressure, are not subjected to damaging stresses.

The foregoing detailed description sets forth the invention in its preferred, practical form, but the invention is to be understood as fully commensurate with the appended claims.

Having thus fully described the invention, what I claim as new and desire to secure by Letters Patent is:

1. In a delivery box for milk containers, the combination of a box body having a bottom and four walls of greater height than the containers housed therein, an ice shelf overlying and resting upon and supported by the tops of said containers in spaced relation to the top of the box body to provide in the upper portion of the box body above the ice shelf a receptacle for a refrigerant, and means for clamping the ice shelf tightly in engagement with the containers to clamp the containers firmly between the ice shelf and the bottom of the box body.

2. In a delivery box for milk containers, the combination of a box body having a bottom and four walls of greater height than the containers housed therein, a perforated ice shelf overlying and resting upon and supported by the tops of said containers in spaced relation to the top of the box body to provide in the upper portion of the box body above the ice shelf a receptacle for a refrigerant, and means for clamping the ice shelf tightly in engagement with the containers to clamp the containers firmly between the ice shelf and the bottom of the box body.

3. In a delivery box for milk containers, the combination of a box body having a bottom and four walls of greater height than the containers housed therein, an ice shelf substantially coextensive with the interior horizontal cross sectional size of the box body overlying and resting upon and supported by the tops of the assembled containers and in spaced relation to the top of the box body to provide in the upper portion of the box body above the ice shelf a refrigerant container, and means for resiliently holding the ice shelf against the tops of the containers to clamp the containers tightly in position between the ice shelf and the bottom of the box body.

4. In a delivery box for milk containers, the combination of a box body having a bottom and four walls of greater height than the containers

housed therein, an ice shelf positioned within the box body and resting upon the tops of the containers therein and spaced from the top of the box body to provide above the ice shelf a container for a refrigerant, opposite walls of the box body being provided at approximately the level of the ice shelf with substantially horizontal abutments facing in the direction of the bottom of the box body, and a resilient clamp pivoted on the ice shelf and adapted to be rotated about its pivot and placed under stress in engagement with said abutments to press the ice shelf firmly against the tops of the containers and clamp the containers between the ice shelf and the bottom of the box body.

5. In a delivery box for milk containers, the combination of a box body having a bottom and four walls of greater height than the containers housed therein, an ice shelf positioned within the box body and resting upon the tops of the containers therein and spaced from the top of the box body to provide above the ice shelf a container for a refrigerant, opposite walls of the box body being horizontally slotted, and a resilient clamping member positioned above and pivoted to the ice shelf and adapted to be rotated and placed under stress with its opposite ends in said slots for the purpose of forcing the ice shelf tightly down upon the assembled containers to clamp said containers between the ice shelf and the bottom of the box body.

6. In a delivery box for milk containers, the combination of a box body having a bottom and four walls of greater height than the containers housed therein, an ice shelf comprising a perforated metal plate substantially coextensive with the interior horizontal cross sectional size of the box body and provided with a peripheral stiffening binding, said ice shelf resting upon the upper ends of the assembled containers in spaced relation to the top of the box body to form above the ice shelf a receptacle for a refrigerant, opposite sides of the box body being provided at about the level of the ice shelf with horizontal slots, and a resilient clamping bar above the ice shelf and pivoted thereto for swinging movement to permit the opposite ends of the bar to be introduced into the slots with the bar under stress to force the ice shelf against the top of the containers and clamp the containers firmly between the ice shelf and the bottom of the box body.

7. In a delivery box for conical containers, the combination of a box body having four walls and a bottom and adapted to receive interiorly such containers arranged alternately in upright and inverted positions, an ice shelf overlying all of the assembled containers in the box body and supported on the upper ends thereof in spaced relation to the top of the box body to provide above the ice shelf a receptacle for a refrigerant, and means for clamping the ice shelf in engagement with said containers.

8. In a delivery box for conical containers, the combination of a box body having four walls and a bottom and adapted to receive interiorly such containers arranged alternately in upright and inverted positions, an ice shelf overlying all of the assembled containers in the box body and supported on the upper ends thereof in spaced relation to the top of the box body to provide above the ice shelf a receptacle for a refrigerant, means for clamping the ice shelf in engagement with said containers, and spacer flanges extending horizontally along the interior of at least

two opposite walls of the box body and engaging with both upstanding and inverted adjacent containers to maintain the latter against tilting.

9. In a delivery box for conical containers,

- 5 the combination of a box body having four walls and a bottom and adapted to receive interiorly conical containers arranged alternately in upright and inverted positions, an ice shelf overlying all of the assembled containers in the box body and supported on the upper ends thereof in spaced relation to the top of the box body to provide above the ice shelf a receptacle for a refrigerant, and means for clamping the ice shelf in engagement with said containers, the bottom of the box body being formed to interfit with at least some of the containers resting thereon.

10. In a delivery box for conical containers, the combination of a box body having four walls 20 and a bottom and adapted to receive interiorly conical containers arranged alternately in upright and inverted positions, an ice shelf overlying all of the assembled containers in the box body and resting on the upper ends thereof in 25 spaced relation to the top of the box body to provide above the ice shelf a receptacle for a refrigerant, and means for clamping the ice shelf in engagement with said containers, the bottom of the box body being provided with projecting 30 portions adapted to extend into the lower recessed ends of the inverted containers.

11. In a delivery box for conical containers, the combination of a box body having four walls and a bottom and adapted to receive interiorly 35 conical containers arranged alternately in upright and inverted positions, an ice shelf overlying all of the assembled containers in the box body and resting on the upper ends thereof in spaced relation to the top of the box body to 40 provide above the ice shelf a receptacle for a refrigerant, and means for clamping the ice shelf in engagement with said containers, the bottom of the box body being provided with projecting portions adapted to extend into the lower recessed ends of the inverted containers and bear 45 against the said ends.

12. In a delivery box for conical containers, the combination of a box body having four walls and a bottom and adapted to receive interiorly conical containers arranged alternately in upright and inverted positions, an ice shelf overlying all of the assembled containers in the box body and supported on the upper ends thereof in spaced relation to the top of the box body to provide above the ice shelf a receptacle for a refrigerant, and means for clamping the ice shelf in engagement with said containers, the bottom of the box body being formed to interfit with the containers resting thereon. 5

13. A delivery box comprising four walls and a bottom and adapted to house containers having recessed ends closed by a cover cap bearing on an appropriate interior seat, the bottom of the box being provided with projections of such shape and size as to extend into the depressions of at least some of the containers to clamp the 10 cap between the projection and the cap seat when the weight of the container and its contents is imposed on said bottom. 15

14. A delivery box comprising four walls and a bottom and adapted to house containers having recessed ends closed by a cover cap bearing on an appropriate interior seat, the bottom of the box being provided with projections of such shape and size as to extend into the depressions of at least some of the containers to clamp the 20 cap between the projection and the cap seat when the weight of the container and its contents is imposed on said bottom, the tops of said 25 projections being recessed to relieve pressure of the projections against the central portion of 30 the caps.

15. A delivery box comprising four walls and a bottom and adapted to house containers of conical form arranged alternately in upright and inverted positions and having recessed ends, the 40 bottom of the box being provided with projections of different sizes adapted respectively to extend into the recessed ends of the upstanding and inverted containers. 45

JOHN A. HOPWOOD.
